GRINDING MACHINE

Hjalmar Emanuel Sjöstrand, Stockholm, Sweden

Application March 18, 1946, Serial No. 655,129
In Sweden August 22, 1944

29 Claims. (Cl. 51—33)

1

The present invention relates to grinding machines and more particularly to such grinding machines for surface grinding of work-pieces of steel or other hard material, in which a rapidly rotating grinding or emery wheel is fed towards or away from the center of a rotating holder for the work-piece, so that the feeding of the grinding wheel with respect to the work-piece will take place along a spiral path in the grinding plane. In known grinding machines of said latter kind the radial feed of the grinding wheel with respect to the rotating holder for the work-piece is rendered possible by mounting the grinding wheel in straight carriage guides in the frame structure, but such guides are subjected to contamination through emery grains or the like, wherefore they are very rapidly worn out and soon lose their capacity of rectilinear precision guiding.

It is a primary object of the present invention to provide a grinding machine of the type set forth, in which the inconveniences found in the known machines are avoided. According to the invention this object has been attained by mounting the grinding wheel and the rotating work-piece holder in supporting members, which are swingable with respect to each other about an axis which is parallel with the axis of rotation of the holder. Since the bearings for the swingable supporting member may be effectively protected against grinding dust or the like, a grinding machine made according to the invention will maintain, also after a very long use, its capacity of precision grinding in the grinding plane, which is a fundamental condition for obtaining a first class surface grinding work.

According to a preferred embodiment of the invention the swingable supporting member is made in the form of an arm, which at the end remote from the swinging axis carries the grinding wheel or the rotating holder for the work-piece. Preferably the supporting arm is made displaceable in the direction of the swinging axis along a slide member, which at its ends is swingably journaled in the frame structure and which preferably includes plane sliding surfaces. By tightening the grip on the sliding surfaces of the slide member, the swingable supporting arm may be rigidly connected with the said member when the machine is being used as a surface grinding machine, so that every play is then avoided at this point, and by arranging the points of journaling the slide member in the frame structure far apart sufficient room may be obtained in the vertical direction to render it possible to dimension the arm proper sufficiently rigid to avoid objectionable springiness in the arm. In the bearings for the guide member every objectionable play may readily be avoided by using bearings of a suitable kind, for example ball bearings or dead center bearings, and said bearings may, as already

2

indicated, readily be effectively protected against grinding dust or the like, so that they will maintain their precision for a long time.

When using the grinding machine according to the invention for surface grinding of work-pieces the necessary lateral feed of the swingable supporting member may be effected by hand, but it is preferable to effect the lateral feed automatically, for instance in dependence of the rotation of the work-piece holder. According to the invention provisions may then be made to vary the speed of rotation of the work-piece holder and/or the angular speed of the swingable supporting arm in such a manner that the speed of feeding the grinding wheel with respect to the work-piece along the spiral shaped feeding path becomes substantially constant independently of the momentary distance of the grinding wheel from the center of the holder, insuring a more effective utilization of the machine.

20 Primarily the grinding machine according to the invention is intended for performing surface grinding of work-pieces of hardened steel or other hard material with the aid of a grinding wheel the plane of which forms a straight or other angle with the work-piece, but it may also be arranged for surface grinding by means of a cupshaped grinding wheel. For said purpose the grinding wheel spindle is preferably journaled in a head which is turnable in the supporting member about an axis which is perpendicular to the grinding spindle.

Except for surface grinding of work-pieces a grinding machine according to the invention may also be used for other purposes such as for cylinder grinding, the work-piece being then placed centrally on the rotatable holder. If it is a question of cylinder grinding of work-pieces having a circular cross-section the swingable supporting member is locked in the desired angular position, whereupon the vertical feed is effected by hand or by means of an automatically operating vertical feed mechanism, with which the machine may be equipped for this purpose. When cylinder grinding articles having a non-circular cross-sectional shape, the supporting member may be swung in unison with the rotation of the holder under control of a template secured to one of the supporting members, with which template a follower arm on the other supporting member cooperates, and when cylinder grinding non-cylindrical bodies of rotation the supporting member may in connection with the vertical feed be swung, under control of a template extending vertically from the table and having a corresponding curvature. With the aid of a cam device of the latter kind form grinding may also be effected on one side only of a non-rotating work-piece.

60 The rotatable holder in a grinding machine ac-

cording to the invention is preferably made dividable in such a manner that only one part extends above the supporting member, so that after removal of said part the supporting member may be used directly as a holder for the work-piece. This is desirable particularly in surface grinding with the aid of a cupshaped grinding wheel and in form grinding.

The grinding wheel is preferably mounted directly on the shaft of a rapidly rotating electric motor which is carried by the corresponding supporting member. For driving the rotatable holder for the work-piece either a separate motor may be used, or the holder may be coupled to the grinding wheel motor through the intermediary of a reduction gear.

Other objects and characteristic features of the invention will be clear from the following detailed description of suitable embodiments with reference to the accompanying drawings.

In said drawings:

Figs. 1 to 3 show a grinding machine according to the invention in which the grinding wheel is supported by the swingable supporting member, Fig. 1 showing the machine in side view and partly in vertical section, Fig. 2 a top view of the machine and Fig. 3 a plan section on the line III-III in Fig. 1.

Fig. 4 shows on a larger scale a cross-section through the swingable supporting arm on the line IV-IV in Fig. 1.

Fig. 5 shows a hand-operated lateral feed screw.

Figs. 6 and 7 show on a larger scale a mechanism for automatically moving the supporting arm in a vertical direction, said mechanism being housed within the arm.

Fig. 8 shows diagrammatically a gear having a variable gear ratio included in the driving mechanism for the rotatable work-piece holder.

Figs. 9 and 10 show schematically the manner of using the machine for form grinding of work-pieces.

Figs. 11 and 12 show in side view and in top view a grinding machine according to the invention, in which the rotatable work-piece holder is journalled in the swingable supporting member.

Fig. 13 shows a cross section through a grinding wheel flange having a bored hub for feeding cooling liquid when using a cup-shaped grinding wheel.

Fig. 14 shows the journalling of the shaft of the grinding motor at the end remote from the grinding wheel.

In the embodiment of the grinding machine shown in Figs. 1 to 3 the frame structure consists of a base plate 1 having a machined upper surface to which a column 2 is secured by means of screws 3. At the top and bottom the column is provided with projecting arms 4 and 5. By means of pivots received in corresponding bearing holes in the projecting arms 4 and 5 a second column 6 is mounted for rotation about an axis *a-a* which is perpendicular to the machined surface of the bottom plate. Said swingable column 6 has a substantially triangular cross-sectional shape and is provided at its two front corners with machined plane sliding surfaces which are parallel with the swinging axis *a-a* of the column. Slidably secured to the said swingable column is a substantially cylindrical hollow arm 7 provided with a rectangular foot 8 having a machined plane end surface, and with two machined bars 9 and 10 secured thereto with

screws 11 and 12, said bars forming together with the said end surface a guide which grips around the prismatic corners of the triangular column 6 and is adapted to be tightened thereagainst by drawing the screws 11 and 12. To render possible a rapid tightening of the guide the screws are provided each with a wrench-like projection, and the said projections are coupled together by means of a link 14, so that both may be drawn simultaneously by means of a single handle 15. At its outer end the arm 7 is provided with a cylindrical bore 16 in which a pivot on a head 17 is received. The head may be locked in every desired angular position by means of a screw 18 which pulls together a longitudinal slit in the arm. The outer end of the head is shaped to form a plate 19 to which an electric motor 20 is secured by screws. On the end of the motor shaft a grinding wheel 21 is mounted by means of a flange and nut. To enable adjustment of the arm 7 in a vertical direction the turnable column 6 is provided with two projections 22 and 23, between which is journalled a screw 24 which extends transversely through the arm 7. The arm 7 is kept in the desired height position by a nut 25, see Fig. 4, which is threaded on to the screw 24, said nut being fitted between two bosses 26 and 27 on the inside of the arm through the intermediary of an axial ball bearing 28. For the turning of the nut 25 to effect vertical adjustment of the arm 7 serves a hand crank 29 on a transverse shaft 30, which is journalled in the arm and coupled with the nut 25 by means of a bevel gear 31, 32.

In the front portion of the table surface of the base plate 1 there is provided a circular hole 35 into which a bearing housing 36 is fitted. The outside of the bearing housing is provided with a flange 37 which bears on a machined surface 40 on the underside of the base plate, where the flange is secured in position by means of a number of screws, not shown. On the inside of the bearing housing has a cylindrical bore closed at its lower end by a bottom ring 38 secured to the housing by means of a number of screws, not shown. A conically bored sleeve 39 provided at the outside with an eccentric cam surface 40 is journalled in the housing 36 by means of two ball bearings 41, 42. A washer 43 serves to protect the ball bearings against dust or the like. The conical bore in the sleeve 39 is intended for receiving a correspondingly shaped conical member 44 on the underside of a circular disc or table 45 which serves to hold the work-piece during the grinding operation.

The rotatable sleeve 39 which carries the work-piece holder is preferably driven from the grinding motor 20. For said purpose the shaft of the latter is provided with a sprocket wheel 46 which by means of a chain 47 drives a chain wheel 48 on an intermediate shaft 49 journalled transversely and centrally in the head 17. To the intermediate shaft 49 is coupled a flexible shaft 50 which extends vertically through the base plate and is provided at its lower end with a sprocket wheel 52, which by means of a chain 53 drives a chain wheel 54 mounted on the lower end of the rotatable holder sleeve 39.

Right opposite to the cam surface 40 on the rotatable holder sleeve 39 the bearing housing 32 is provided with a boss 55 in which is provided a radial bore 56 for a sliding pin 57 which carries at its outer end a rectangular head 58 having an extension 59 between which and a fixed pin 60 there is tensioned a spring 61 which strives to

hold the sliding pin pressed against the cam surface; see Fig. 3. On account of the action of the cam and the spring, the pin 57 will evidently move back and forth once for every revolution of the sleeve 39. Pivotally mounted on the sliding pin head 58 are two ratchets 62, 63, which are adapted by means of a shifting member 64 to be brought into operative position with respect to a ratchet wheel 65 journalled in the base plate, said ratchet wheel being thus moved stepwise by the pin 57 in one direction or the other depending upon which one of the two ratchets that occupies its operative position. The ratchet wheel 65 is mounted on a bearing sleeve 66 threaded onto a depending bearing pin 67, and it carries at its lower end a sprocket wheel 68. Said sprocket wheel drives by means of a roller chain 69 a chain wheel 70 mounted on the lower end of an intermediate shaft 71, which is carried vertically through the base plate. At its upper end said intermediate shaft is provided with a flange 72 which rests on the upper surface of the table, and with a screw-threaded extension 73 provided with a hand operated nut 74 intended for fixing a slotted arm 75 having a handle 75a in any desired angular position. The handle 75a can be used when it is desired to swing the grinding wheel by hand. By means of a link 76 the arm 75 is pivotally connected with the lower projection 23 of the swingable column 6, whereby the turning movement of the arm is transmitted to the column, so that the latter will swing the grinding wheel 21 towards the center of the rotatable table 45 according as the rotation of the table progresses.

By shifting the pivot pin on the link 76 along the slot in the arm 75 a more rapid or slow feeding of the grinding wheel towards the center of the rotatable work-piece holder may be obtained, and by selection of a suitable length for the link the feeding speed may be brought to increase towards the center or to decrease towards the periphery. In such manner a compensation is obtainable for the difference in the speed of the work-piece past the grinding wheel at different distances from the axis of rotation of the table. The positive feeding of the grinding wheel in dependence upon the rotation of the work-piece holder may be disconnected by loosening the hand operated nut 74.

The extension 59 on the reciprocating pin 57 referred to above reaches the center of a diaphragm pump 77, where it actuates the diaphragm. Said pump, which is shown diagrammatically only in Fig. 3, is intended to pump soap water or other cooling liquid through tube or hose lines, not shown, onto the grinding wheel.

When surface or plane grinding a larger work-piece with the aid of the machine described above, the work-piece is secured centrally on the rotatable holder or face plate 45. By means of the lateral feed mechanism described the grinding wheel 21 is then fed from the periphery of the work-piece towards the center of the holder at an increasing speed by swinging the supporting arm 7, the grinding wheel then consecutively grinding the work-piece along a spiral path which covers the entire surface of the work-piece. If instead the surfaces of a number of smaller work-pieces shall be ground, the work-pieces are preferably secured to the holder so as to form a ring about its center.

The accuracy with which the surface or plane grinding may be carried out by means of the machine described is evidently dependent among

other things thereon that there is no objectionable play, neither between the supporting arm and the swingable column or between the latter and the frame structure. Any possible play between the supporting arm and the swingable column may be eliminated entirely during the surface grinding operation by previously tightening the screws 11 and 12 by means of the handle 15. The bearings at the ends of the swingable column preferably are made as dead center pins having conical points, or as ball bearings arranged in the arms 4 and 5 projecting from the frame column 2, whereby every play may be avoided also in the bearings. In the latter case it is often preferable to secure the pivots detachably in the swingable column. The lower one of said pivots may then be made sufficiently long to project down through an opening in the base plate 1, whereby it is rendered possible to place the mechanism for swinging the column and the supporting arm carried thereby entirely below the machined table surface. The positioning in the grinding machine shown of the bearings for the swinging column far apart prevents the springiness which is unavoidable at shorter bearing distances. The direction of rotation of the grinding wheel and of the work-piece holder should preferably be selected so as indicated by the arrows, i. e. the grinding wheel should operate in a direction opposite to the direction of rotation of the holder and towards the column. The grinding dust will then be thrown over a surface of the work-piece, that has not yet been ground and away from the operator, so that it can be readily collected by means of a funnel or the like. The cooling liquid flows down into a channel 78 provided around the edge of the table, from which channel openings 79 and pipes, not shown, conduct the liquid back to a container under the table.

40 The grinding machine according to Figs. 1 to 3 may also be used for cylinder grinding of cylindrical work-pieces by means of the periphery of an ordinary grinding wheel. The work-piece is then placed on the rotatable holder concentrically, the grinding motor is turned through 90°, for example, the automatic lateral feed is disconnected by loosening the hand operated nut 74, and an auxiliary device adapted for locking the swingable supporting arm in the desired angular position is mounted instead on the machine. Such an auxiliary device, which may be used also during surface grinding operations for carrying out the lateral feed by hand, is shown in Fig. 5.

45 According to said figure the auxiliary device consists of a screw spindle 80 provided with a crank 81, a bearing 82 and a nut 83 for the feed. From the bearing 82 and from the nut 83 project at right angles to the screw spindle cylindrical pins 84 and 85 respectively. When the auxiliary device shown is used, the pin 84 projecting from the bearing is inserted in a bored and reamed hole 86 in the table 1, whereas the pin 85 on the nut is inserted into a similar hole 87 at the outer end of the lower projection 23 of the turnable column 6, whereupon the supporting arm for the grinding wheel is set in the desired lateral position by turning the screw spindle by means of the hand crank 81.

50 The vertical feed required during the cylinder grinding operation may be effected by hand by means of the crank 29. It is more convenient, however, to equip the machine with an automatic vertical feed device, which may be thrown in when desired. Such a mechanism is shown in

55 Figs. 6 and 7.

70 The vertical feed required during the cylinder grinding operation may be effected by hand by means of the crank 29. It is more convenient, however, to equip the machine with an automatic vertical feed device, which may be thrown in when desired. Such a mechanism is shown in

75 Figs. 6 and 7.

In said mechanism the nut 25 screwed onto the vertical feed screw 24 is provided not only with the bevelled gear wheel 32 intended for the hand feed but also with a ratchet wheel 90. Adapted to cooperate with the latter are two ratchets 91 and 92 which are pivotally supported each at the end of a corresponding link 93 or 94, said links being carried in a slot in a bracket 95 secured to the wall of the supporting arm 7. Between pins 96 on the ratchets 91 and 92 is 10 stretched a spring 97. For the purpose of setting any one of the ratchets in operative position, or both ratchets simultaneously in inoperative position, there is provided a cam disc 98 which is coaxial with the ratchet wheel and mounted on a sleeve 99 surrounding the screw spindle 24, said sleeve projecting through the wall of the supporting arm and carrying on its projecting end an operating handle 100. When the cam disc 98 takes up the position shown in Fig. 6, it 20 holds the upper ratchet 91 out of engagement with the ratchet wheel 90, so that only the lower ratchet 92 is operable for the purpose of driving the wheel in the direction of the arrow. By 25 turning the cam disc 98 by means of the operating handle 100 the lower ratchet may instead be lifted out of engagement with the ratchet wheel, and the upper ratchet be permitted to take up instead an operative position for turning the nut in the opposite direction, and alternatively both ratchets may be lifted away from their operative positions, the automatic vertical feed mechanism being then entirely disconnected. For the operation of the ratchets serves, in the embodiment shown, the transverse intermediate shaft 49 driven from the grinding motor, on which shaft there is mounted for that purpose an eccentric disc 101 which actuates a rod 102 which is mounted for axial displacement in the supporting arm 7. By means of the mechanism described the automatic vertical feed of the grinding wheel in dependence upon the rotation of the grinding motor is thus effected at a constant speed.

Instead of driving the holder for the work-piece at a constant speed as shown in Figs. 1 to 3, and compensating the tangential feeding speed, which in surface grinding varies with the distance of the grinding wheel from the axis of rotation, by altering the radial feeding speed, it is possible, of course, alternatively to increase the speed of rotation of the work-piece according as the grinding wheel approaches the center of the holder while effecting the radial feed at a substantially constant rate. The desired increase of the speed of rotation of the holder may then be effected by incorporating, in the driving mechanism for the rotatable holder, a gearing having a variable gear ratio. Such a gearing may be designed in the manner illustrated by way of example in Fig. 8.

According to said figure, the holder sleeve 39 is driven by means of a gear wheel 103 mounted at the lower end of the sleeve from a smaller gear wheel 104 secured to a friction disc 105 which is driven from the flexible shaft 50 by means of a small friction wheel 106. The latter is mounted on the end of an arm 107 which is swingable about a pin 108 depending from the base plate by means of a hub 109 on which the arm is pivoted to swing in a plane through the pin. Cooperating with the arm 107 is an eccentrically journaled cylinder 111 provided with an operating arm 110 and adapted, upon being turned by means of the operating arm, to lift the arm 107 and press

the small friction wheel 106 into engagement with the underside of the friction disc 105. Adapted to cooperate with the arm 107 is a cam disc 112 mounted on an extension of the lower bearing pin of the swingable column 6, the arm being pressed against said cam disc by a spring 113, so that simultaneously with the feeding of the grinding wheel towards the center of the work-piece holder in connection with the swinging-in of the supporting arm 7, the arm 107 and thus also the driving friction wheel 106 is swung towards the center of the friction disc 105. Through a suitable shaping of the cam 112 it is evidently possible to secure that the tangential feeding speed of the rotatable table disc 45 or of the work-piece respectively with respect to the grinding wheel remains constant during the entire surface grinding operation.

To render possible a reversal of the direction of rotation of the work-piece holder, as may be desirable when using the machine for cylinder grinding, for example, the hub 109 of the arm 107 is provided with a projecting finger 114 with which an eccentric disc 115 may be brought into engagement by turning the latter by means of the operating arm 116.

The grinding machine shown in Figs. 1 to 3 is also suitable for form grinding of a work-piece in a radial direction. When the machine is to be used for said purpose the automatic lateral feed mechanism is again disconnected by loosening the hand operated nut 14, whereupon a follower arm 120 similar to the one shown in Fig. 9, for instance, is bolted to the lower projection of the swingable column 6, possibly after disconnection of the link 76. Centrally on the rotatable face plate or table 45 is secured a template 121 having the desired contour, with which template the end of the follower arm is brought into engagement by connecting a tensioned spring 122 between the arm and a point on the base plate. During rotation of the face plate 45, the spring 122 forces the arm 120 to follow the contour of the template 121, so that cam discs or other work-pieces secured to the face plate may be ground automatically in accordance with the shape of the template or pattern. In this connection the automatic vertical feed mechanism may also be used, as in ordinary cylinder grinding.

In case the machine is to be used for form grinding of work-pieces in a vertical direction after a template it is suitable to mount on the swingable supporting member a follower arm 125, as shown in Fig. 10, and to mount on the upper surface of the grinding table, possibly after removing that portion 45 of the rotatable holder which projects above the table surface, an upright template 126 formed at one of its vertical sides with the profile 127 according to which the work-piece is to be ground. A spring, not shown, holds the follower arm 125 in engagement with the template 126, so that in connection with the vertical feed there is transmitted to the swingable supporting member a lateral movement, which corresponds to the profile of the template. This kind of lateral guiding of the swingable supporting member may be used both in form grinding of bodies of rotation, the work-piece being then secured to the rotatable holder, as well as in form grinding on one side of the work-pieces which are secured directly to the table surface of the base plate.

The embodiment of the grinding machine according to the invention, which is shown in Figs. 11 and 12, differs from the one disclosed in Figs.

1 to 3 substantially therein that the grinding wheel is journalled directly in the frame structure, i. e. in the stationary supporting member, whereas the rotatable holder for the work-piece is carried by that supporting member which is swingable with respect to the frame. The frame is made in the form of a box 130 having double walls and two vertical sides open, the grinding motor with the grinding wheel 132 being fixably mounted in the roof portion 131 of the frame box. Journalled between the roof portion 131 and the bottom portion 133 of the frame box is the swingable column 134 along which the supporting arm 135 is vertically displaceable. At the outer end of the supporting arm 135 a face plate 136 intended to serve as a holder for the work-piece is rotatably journalled about an axis which is parallel with the swinging axis of the supporting arm or column respectively. The rotatable holder 136 is here shown as driven from a separate electro-motor 137. The mechanism for automatically swinging the supporting arm 135 has been left out from the drawing for the sake of simplicity as has also the mechanism for automatically effecting the vertical feed of the supporting arm. Said mechanisms may be of the same design as those previously described.

It should be clear that also in the machine shown in Figs. 11 and 12 the grinding motor may be mounted in a turnable head, so that alternatively the grinding may be effected by means of a cup-shaped grinding wheel. It is also possible to remove the rotatable work-piece holder and use the plane upper surface of the supporting arm for securing the work-piece.

In certain cases the motor 137 for driving the rotatable holder may advantageously be replaced by an oil turbine which may be varied with respect to its speed by automatic choking of the oil supply through a regulating valve connected with the movable supporting member, whereby an absolutely uniform transmission free from vibrations is obtainable. A friction gearing or other separate gearing having a variable gear ratio may then be dispensed with.

If the machine according to Figs. 1 to 3 is to be used for surface grinding by means of a cup-shaped grinding wheel mounted on the grinding motor shaft, the head carrying the motor being then first turned through one quarter of a revolution so that the motor shaft forms right angles with the rotating face plate 45, it is of importance that all axial play is eliminated. This object may be secured by journalling the end of the motor shaft which is remote from the grinding wheel in the manner shown in Fig. 13. According to said figure the shaft is provided with a double axial bearing, the intermediate race 140 of which is secured to the shaft by means of a screw 141. Between the outer race 142 and the bottom of the bearing housing 143 is inserted a tensioned helical spring 144, which presses the inner race 145 against a washer 147 supported on the bearing shield 146. Since the radial bearing 148 of the motor permits of a free play in the axial direction, the motor shaft becomes elastically yielding from a definite normal position in the direction away from the work-piece, whereby objectional axial play is eliminated.

When grinding with a cup-shaped grinding wheel the cooling offers certain difficulties. A simple arrangement for effectively supplying cooling liquid to the portion of the work-piece embraced by the grinding wheel is shown in Fig. 14. According to said figure there is mounted on the

motor shaft by means of a hub 150 a fixing flange 151 for the grinding wheel 152 which is indicated in dot-and-dash lines. In the end of the hub nearest to the motor there is provided an annular channel 153, the innermost part of which is positioned farther away from the center than its open outermost portion. For the opposite or lower end of the hub one or more holes 154 are bored onto the innermost portion of the annular channel 153. If soap water or other cooling liquid is supplied to the annular channel through a pipe 155, the water will, on account of the centrifugal force, be pressed towards the bottom of the annular channel 153 and through the bores 154 further on to the inside of the cup-shaped grinding wheel 152, where it is flung by the centrifugal force towards the inner wall of the disc and further in under the working edge 156 of the grinding wheel. The cooling water is suitably supplied to the pipe 155 from the diaphragm pump 17.

The invention is not limited, of course, to the embodiments shown on the drawings and described in detail above but modifications of different kind are conceivable within the scope of the invention. As a holder for the work-piece there may thus be used, instead of the face plate shown in Figs. 1 to 3, a three-jawed chuck, for instance, a magnetic chuck, et cetera, the conical fixing member adapted to be inserted in the rotatable sleeve positioned entirely below the plane upper surface of the table then facilitating the exchange of holders. As already indicated the machine may, of course, also be used when the holder is removed. For surface grinding a cup-shaped grinding wheel is then preferably used, the grinding wheel being moved back and forth with respect to the work-piece by swinging the supporting arm.

In cases when it is desired to use as a holder for the work-piece a magnetic chuck fed with direct current, it is suitable to take up an axial bore in the conical securing pin, one pole of the current source being then connected to a centrally positioned isolated sliding contact at the lower end of the pin, whereas the other pole may be connected to the metal body of the chuck. If it is desired instead to have both poles insulated, an insulated slip ring may be arranged around the sliding contact, a brush holder of Turbex or the like being mounted below the pin to permit two carbon brushes to press in an axial direction against the central contact and the slip ring.

In all the embodiments described the grinding wheel may, of course, be replaced by a cutting tool, for instance a milling cutter having hard metal knives. Furthermore, some of the detail constructions described may be used in other combinations and in other kinds of working machines than those described by way of example. This is true particularly with respect to the manner of journalling the swingable and vertically displaceable supporting members and with respect to the arrangement of an angular gear cooperating with the vertical feed screw for adjustment of the vertical position of the grinding wheel. Even other modifications are conceivable within the scope of the invention.

What is claimed is:

1. A machine for grinding plane surfaces, comprising in combination a frame, a rigid arm mounted on said frame so as to be swingable about a stationary axis, a first spindle rotatably mounted with its axis in fixed position in said frame, a second spindle rotatably mounted at the free end of said swingably mounted rigid arm

with its axis in fixed position with respect to said arm, a grinding wheel mounted on one of said spindles, a holder for the work-piece mounted on the other one of said spindles, the axis of rotation of the spindle carrying the work-piece holder being parallel with the swinging axis of the rigid arm, an electric motor to cause the spindle carrying the grinding wheel to rotate at a high speed, means including a reduction gear adapted to cause the spindle carrying the work-piece holder to rotate at a low speed, means for adjusting the position of said rigid arm in the direction of its swinging axis thereby enabling the distance between the grinding wheel and the work-piece holder to be adjusted and means for holding the rigid arm in fixed axial position after adjustment.

2. A grinding machine as claimed in claim 1, in which the plane of rotation of the grinding wheel forms a right angle with the plane of rotation of the work-piece holder.

3. A grinding machine as claimed in claim 1, in which the plane of rotation of the grinding wheel is parallel with the plane of rotation of the work-piece holder.

4. A grinding machine as claimed in claim 1, in which the angle between the plane of rotation of the grinding wheel and the plane of rotation of the work-piece holder is adjustable.

5. A grinding machine as claimed in claim 1, in which the work-piece holder is adapted to be driven from the grinding wheel motor through the intermediary of a reduction gear comprising a flexible shaft.

6. A grinding machine as claimed in claim 1, in which the work-piece holder is dividable and comprises a sleeve having a tapered bore, which is journaled in the frame of the machine, the upper part of the work-piece holder being adapted to be detachably secured in the tapered bore of said sleeve by means of a correspondingly tapered pin.

7. A grinding machine as claimed in claim 1, in which the reduction gearing is adapted to change its gear ratio automatically in dependence of the distance of the grinding wheel from the center of the work-piece holder.

8. A grinding machine as claimed in claim 1, in which the reduction gearing consists of a friction disc with which a driving wheel cooperates at a variable distance from the center of the disc, the said driving wheel being journaled at the free end of an arm which is swingable about an axis that is parallel with the axis of rotation of the friction disc under the influence of a cam which is turned simultaneously with the swingable supporting member.

9. A grinding machine as claimed in claim 8, in which said rigid arm is swingable also in a plane through the swinging axis parallel with the axis of the friction disc, the arm being adapted to take up a position in which the driving wheel is out of engagement with the friction disc and to be brought from said position to an operating position through the shifting of a cam device cooperating therewith.

10. A grinding machine as claimed in claim 1, in which the reduction gearing consists of a friction disc with which a driving wheel cooperates at a variable distance from the center of the disc, the said driving wheel being journaled at the free end of an arm which is swingable about an axis that is parallel with the axis of rotation of the friction disc under the influence of a cam which is turned simultaneously with the swing-

able supporting member and wherein the swingable arm for the grinding wheel is adapted to be operated through a hand-operated cam or the like, by means of which the arm may be locked in any desired position with respect to the center of the friction disc at the opposite side thereof.

11. A grinding machine as claimed in claim 1, comprising also a mechanism for automatically displacing the swingable rigid arm, in the direction of the axis of rotation of the work-piece holder for the purpose of facilitating the use of the machine as a cylinder grinding machine.

12. A grinding machine as claimed in claim 1, in which the adjustment of one of the supporting members in the direction of rotation of the holder is effected by means of a screw and a nut, one of the said screw members being adapted to be rotated by the motor for driving the grinding spindle and the rotatable work-piece holder through the intermediary of a movement transmitting mechanism.

13. A grinding machine as claimed in claim 12, in which one of the screw members carries a ratchet wheel stepping mechanism, which is driven from the electric motor through the intermediary of a cam.

14. A grinding machine as claimed in claim 1, characterized in that the adjustment of one of the supporting members in the direction of rotation of the holder is effected by means of a screw and a nut operated by a ratchet wheel stepping mechanism and wherein the stepping mechanism comprises two ratchets operating in different directions, means being provided for making one of said ratchets operable or both inoperable.

15. A grinding machine as claimed in claim 14, in which the ratchets are adapted to cooperate as well with a cam disc which is coaxial with the ratchet wheel and is adapted to be turned from without, said cam disc serving by its rotation to lift one or both ratchets out of engagement with the ratchet wheel.

16. A grinding machine as claimed in claim 1, in which the adjustment of one of the supporting members in the direction of rotation of the holder is effected by means of a screw and a nut operated by a ratchet wheel stepping mechanism and wherein a driving cam for the stepping mechanism is positioned on a transverse shaft journaled in the swingable supporting member and is adapted to cooperate with a rod coaxial with the supporting arm and displaceable in its longitudinal direction, said rod being adapted to actuate, at the end remote from the cam, the ratchets through the intermediary of two links, which at their free ends pivotally support the two ratchets between which a spring is tensioned.

17. A grinding machine as claimed in claim 1, in which the swingable supporting member is provided with a follower member adapted for cooperation with a curved disc or template arranged on the rotatable work-piece holder, so that the machine may be used for form grinding of work-pieces in a radial direction.

18. A grinding machine as claimed in claim 1, in which the swingable supporting member is provided with a follower for cooperation in connection with the vertical feed with a template extending from the other supporting member.

19. A grinding machine as claimed in claim 1, in which the grinding wheel is mounted directly on the shaft of an electromotor, said motor being provided at the end remote from the grinding wheel with a double axial bearing which is pressed by a spring into engagement with the

outer side of the bearing shield for the purpose of avoiding objectionable axial play.

20. A grinding machine as claimed in claim 1, in which the grinding wheel spindle is provided with a flange for mounting a cup-shaped grinding wheel, said flange being provided on the side nearest to the motor with an annular channel for receiving soap water or the like, the innermost portion of said channel being positioned farther away from the axis than its outermost open portion and being arranged to communicate with the opposite lower side of the grinding wheel through a number of axially extending channels.

21. The grinding machine of claim 1 wherein the grinding wheel spindle is driven by an electric motor and the work-piece spindle is driven by the said motor through the intermediary of a reduction gear comprising a flexible shaft, said electric motor being mounted in a head which is rotatable about an axis perpendicular to the grinding wheel spindle, said flexible shaft being connected to a transverse intermediate shaft included in the reduction gearing and journaled in the head.

22. A grinding machine, suitable for surface grinding, having one supporting member for a grinding wheel and another supporting member for a work-piece, in which one of the supporting members is swingable with respect to the other about an axis perpendicular to the grinding plane, the swingable supporting member being displaceable in the direction of the said swinging axis along a guide having sliding surfaces, which guide is swingably journaled in the other supporting member and means for securing the swingable supporting member in fixed axial position against said sliding surfaces.

23. A machine for grinding plane surfaces, comprising in combination a frame, a rigid arm mounted on said frame so as to be swingable about a stationary axis, a first spindle rotatably mounted with its axis in fixed position in said frame, a second spindle rotatably mounted at the free end of said swingably mounted rigid arm with its axis in fixed position with respect to said arm, a grinding wheel mounted on one of said spindles, a holder for the work-piece mounted on the other one of said spindles, the axis of rotation of the spindle carrying the work-piece holder being parallel with the swinging axis of the rigid arm, means to cause the spindle carrying the grinding wheel to rotate at a high speed, means to cause the spindle carrying the work-piece holder to rotate at a low speed, means for adjusting the position of said rigid arm in the direction of its swinging axis thereby enabling the distance between the grinding wheel and the work-piece holder to be adjusted, means for holding the rigid arm in fixed axial position after adjustment, and means for automatically swinging said rigid arm to cause a feeding movement of the grinding wheel in the grinding plane towards or away from the center of rotation of the work-piece holder.

24. A grinding machine as claimed in claim 23, in which the mechanism for automatically swinging the swingable supporting member is adapted to operate in dependence upon the rotation of the work-piece holder.

25. A grinding machine as claimed in claim 23, 70 in which the mechanism for automatically swing-

ing the swingable supporting member is designed so as to cause the swinging movement to take place at an angular velocity which increases during the approach of the grinding wheel to the center of the work-piece holder.

26. A grinding machine as claimed in claim 23, in which the mechanism for automatically swinging the swingable supporting member comprises a ratchet wheel coupled to the swingable supporting member and adapted to be moved stepwise in one direction or the other under control of a cam which rotates together with the work-piece holder.

27. A grinding machine as claimed in claim 23, 15 in which the mechanism for automatically swinging the swingable supporting member comprises a ratchet wheel coupled to the swingable supporting member and adapted to be moved stepwise in one direction or the other under control of a cam which rotates together with the work-piece holder and wherein said ratchet wheel is adapted to drive an intermediate shaft which is parallel with the swinging axis of the supporting member and is coupled through a radially extending arm and a link with a point on the supporting member positioned at some distance from the swinging axis, the pivotal connection between the link and the radially extending arm being displaceable along the arm for the purpose of changing the character of the transmission of movement.

28. A grinding machine as claimed in claim 23, provided with a detachable hand-operated screw mechanism for swinging the swingable supporting member.

29. A machine for grinding plane surfaces, comprising in combination a frame, a guide member swingably journaled at its ends in said frame, a rigid arm slidably supported on said guide member, means for adjusting the position of said arm 40 on said guide member in the direction of the swinging axis of the latter, means for locking the arm in its adjusted position on said guide member, a first spindle journaled in said frame, a second spindle journaled at the free end of said 45 arm, a grinding wheel mounted on one of said spindles, a holder for the work-piece mounted on the other one of said spindles, the axis of rotation of the spindle carrying the work-piece holder being parallel with the swinging axis of the rigid arm, means to cause the spindle carrying the grinding wheel to rotate at a high speed, means to cause the spindle carrying the work-piece holder to rotate at a low speed, and means for slowly swinging said rigid arm to cause a 50 radial feeding movement of the grinding wheel in the grinding plane towards or away from the center of rotation of said work-piece holder.
